FOAM PACKAGING TRAY FOR FOOD

Donald K. Jewell, Naperville, Ill., assignor to
Restaurant Technology, Inc.

Filed Dec. 6, 1974, Ser. No. 530,209

Term of patent 14 years

Int. Cl. D9—03

U.S. Cl. D9—235

FIG. 1

FIG. 2

FIG. 3

FIG. 5

FIG. 6

FIG. 7

FIG. 1 is a top perspective view of a foam packaging tray for food showing my new design;

FIG. 2 is a front elevational view;

FIG. 3 is a side elevational view, the opposite side being a mirror image of the side shown;

FIG. 4 is a rear elevational view;

FIG. 5 is a top plan view;

FIG. 6 is a bottom plan view; and

FIG. 7 is a perspective view on a reduced scale in an open position.

I claim:

The ornamental design for a foam packaging tray for food, substantially as shown and described.
